(57) **CLAIM**

The ornamental design for a tire, as shown and described.

DESCRIPTION

FIG. 1 is a front view of a tire showing my new design;
FIG. 2 is a rear view thereof;

FIG. 3 is a top plan view thereof, for which the bottom plan view is the same;

FIG. 4 is a right side view thereof;

FIG. 5 is a left side view thereof;

FIG. 6 is an enlarged view taken along line 6-6 in FIG. 1; and,
FIG. 7 is a cross-sectional view taken along line 7-7 in FIG. 4
and along line 7'-7' in FIG. 6.

The broken lines in the Figures show portions of the tire that form no part of the claimed design.
